UNITED STATES PATENT OFFICE.

EUGENE B. WHELAN, OF OMAHA, NEBRASKA.

STEAM-CIRCULATING BY-PASS AND RELIEF VALVE.

1,351,314.

Specification of Letters Patent. Patented Aug. 31, 1920.

Application filed February 1, 1919. Serial No. 274,521.

To all whom it may concern:

Be it known that I, EUGENE B. WHELAN, a citizen of the United States, and a resident of Omaha, in the county of Douglas and State of Nebraska, have invented certain new and useful Improvements in Steam-Circulating By-Pass and Relief Valves, of which the following is a specification.

My present invention relates generally to valves for steam engines, especially steam locomotives, of the piston valve type, and particularly to valves which function as by-pass and vacuum and compression relief valves, my object being the provision of an arrangement whereby low pressure steam is positively circulated through the cylinders when a locomotive is drifting for purposes of lubrication, in addition to the usual functions of a valve of this type.

A further object of my invention is to provide an arrangement of the above nature wherein by cutting off the feed of steam and certain slight changes readily made, the valve may be made to operate as the ordinary by-pass and vacuum and compression relief valves.

A still further object is the provision of a steam circulating by-pass and relief valve in which the provision is made for a positive feed of steam, that is, low pressure steam, to the high pressure steam space of the valve chamber in addition to the forced circulation through the cylinders so that in case of continued drifting, all service requirements are met by a measured feed of low pressure steam through the action of the piston valve.

Still further objects and the resulting advantages of my present invention, will be made plain in the course of the following description, reference being had to the accompanying drawings, forming a part of this specification, in which:—

Figure 1 is a vertical longitudinal section through portions of a piston valve and through my improvements in connection therewith,

Figs. 2, 3 and 4 are horizontal sections taken respectively on lines 2—2, 3—3 and 4—4 of Fig. 1,

Fig. 5 is a vertical transverse section taken substantially on line 5—5 of Fig. 1;

Fig. 6 is a detail perspective view of the pilot valve,

Fig. 7 is a detail perspective view of the 55 plug of the pilot valve,

Fig. 8 is an elevation showing the steam supply controlling means, and

Fig. 9 is a plan view of a portion of Fig. 8, as hereinafter described.

Referring now to these figures, I have in Fig. 1 in particular shown a piston valve casing generally indicated at 10, in which a piston valve (not shown) moves in the portions 11 and 12 upon opposite sides of the 65 main high pressure steam space 13.

The piston valve casing 10 communicates with the steam cylinders (not shown) in the usual way, and has upper passages 14 and 15 which in accordance with my improvements are cut through the upper portion of its wall, or at another suitable point, as indicated at 16, and communicates with the side channels 17 and 18 of a valve block 19 secured by bolts 20 or by other suitable means, 70 to the upper portion of the casing 10.

This valve block 19 has vertical valve bores in spaced parallel relation to receive vertically movable valves 21 and 22, and each of these bores have vertically spaced 75 valve seats 23 with which the vertically spaced valve faces 24 of valve 22 co-operate. Between the valve seats 23 of each bore an enlarged chamber 25 is formed which communicates with the respective channel 17, 18, 85 and above the upper valve seat 23, each bore has an enlarged chamber 26, as well as an enlarged chamber 27 below the lower valve seat 23. The lower enlarged chambers 27 are in communication through a channel 28 90 and the upper chambers 26 are likewise in communication through a channel 29 at the lower ends of a central vertical passage 30, leading downwardly from an upper chamber 31 located in the block 19, having a side 95 opening 32 and opposed side channels 33 which respectively lead from the chamber 31 to the upper end of the two valve bores as shown, the upper extremities of which valve bores are closed by plugs 34.

Each of the valves 21 and 22 has guides 35 which slide in portions of the respective valve bore above the two valve seats 23, so that with the valves lowered away from their seats, as seen in Fig. 1, the two side 105 steam channels 17 and 18 are in communication through both the lower connecting channel 28 and the upper connecting chan-

nel 29. This communication is under ordinary running conditions cut off by virtue of the fact that the valves 21 and 22 are held against their seats, by the pressure within 5 the main steam space 13 through the vertical opening 36 leading from the main steam space and upwardly to the lower end of the two valves.

Above the upper enlarged chambers 26 of 10 each of the valve bores, each valve has a piston 37 and a second reduced piston 38 in the upper reduced portion of the bore, the upper end of the valve being engaged by a spring 39 compressed between the upper end 15 of the upper piston 38 and the plugs 34 closing the upper end of its bore.

Each of the valves 21 and 22 is furthermore provided with an axial channel 40 extending therethrough from its upper end to 20 a lower valve chamber formed within the valve as seen at 41, the upper portion of which forms a seat for a vertically movable pilot valve 42, the latter seating upwardly and normally held in closed position by the 25 pressure of the main steam space 13. In its lower open position, the pilot valve 42, which has upwardly extending guides 43, is provided with a lower central boss 44 which rests upon the upper flat face of a plug 45 30 threaded into a diaphragm having an annular series of openings 46 around the valve 42 and through which the pressure from the main steam space 13 finds its way, to normally seat the pilot valve.

In addition to its axial channel or bore 40, each valve 21, 22, has a lower enlarged counterbore and an annular series of openings 47 through its wall around the counterbore, so that steam which flows downwardly 40 through the valve with the pilot valve 42 dropped to open position, may flow outwardly in volume dependent upon the area of the openings 47, into the lower steam chambers 27 of the valve block 19 and thence 45 upwardly past the lower guides 35 to join with steam passing between the channels 17 and 18 with the two valves 21 and 22 open, and with the steam passing down from the upper central steam chamber 31 through 50 the channel 30 and upper steam chambers 26 as well as connecting channels 29.

To provide for the steam action as just above described, a low pressure steam supply pipe 48 leads to the valve block 19 and is 55 connected to the opening 32 of the upper central steam chamber 31 and it is this low pressure, which, with the valves 21, 22 in their upper closed position, simply remaining inactive, at once becoming active upon 60 failure of pressure within the high pressure steam space 13 when the locomotive throttle is closed and the locomotive is drifting, the low pressure steam then entering as previously described into the channels 17 and

18 through the open valve so as to provide 65 for a continuous supply of low pressure steam to be circulated through the steam cylinders, carrying lubrication thereto, in addition to their usual function in connection with the formation of a by-pass between the cylinder ends and the relief both 70 of vacuum and compression in the cylinder. In the last described action of the valves 21 and 22 when open, various surfaces thereof are of course subject to the action of the 75 low pressure steam, notably among these being the lower surfaces of the lower enlarged pistons 37 as well as the upper surfaces of the smaller upper pistons 38, the latter of which are also engaged by the springs 39, 80 considering which, it is obvious that by slight adjustment the valves 21 and 22 may be perfectly balanced to drop readily and be opened to the open position as shown in Fig. 1 when the high pressure steam fails, 85 due to the closing of the throttle, and to move instantly to closed position when the throttle is again opened, as well as for the purpose of defeating all danger of the valve sticking.

It is furthermore obvious that when the valves 21 and 22 lower to their open position, their pilot valves 42 also drop to open position so that the low pressure steam from the upper chamber 31 finds its way through 95 the channel 33 and the axial bore 40 of the two valves and thence downwardly through the diaphragm openings 46 to the lower counterbores of the valves, and consequently into the main steam space 13 of the piston 100 valve through the openings 36 so that in case of continued drifting all service conditions are readily met by the measured supply of steam to the cylinders through the main piston valve.

As seen in Figs. 8 and 9, the low pressure steam supply pipes 48 lead from a pressure reducing valve 49, to the latter of which steam is supplied through a pipe 50 controlled by a cut-off valve 51 which is normally closed and has a projecting stem 52.

The controlling valve 51 also controls the supply of steam through a pipe 53 to the lubricator 54 connected by a pipe 55 with the pressure reducing valve 49 and consequently the supply pipe 48 to the two cylinders. The controlling valve 51 is furthermore placed adjacent to the main steam throttle 56 having, in accordance with my present improvement, a side tappet 57 for 110 engagement with the stem 52 of the controlling valve 51 to open this valve when the throttle 56 is pushed to closed position. This tappet is, however, controlled by a latch 58 so that if desired, the operator in 115 closing the throttle 56 may draw the tappet 57 outwardly along the throttle lever and thus out of contact with the valve stem 120

90

120

125

52, the tappet resting, when the throttle is closed in this way, upon a tappet rest indicated at 59 in Fig. 9.

Thus, in all ordinary stops when the 5 throttle is closed, the tappet 57 engages the valve stem 52 and low pressure steam is thus supplied through the low pressure steam supply pipe 48, carrying the lubricant therewith, while at final stops, when for instance the locomotive is run into a round 10 house, the tappet 57 is shifted by means of the latch 58 and the controlling valve 51 remains closed when the throttle is closed.

From the foregoing description of the 15 construction and operation of my invention, it is also to be observed that if for any reason it is not desired to supply low pressure steam through pipe 48, or if for any reason it becomes impossible to do so, these 20 pipes may simply be disconnected from the valve blocks 19 and openings 32 will thus act simply as ports to the atmosphere. In this case, the upper vertical channel 30 between the upper central chamber 31 and the 25 upper connecting channel 29 is plugged as unless steam is utilized, this vertical channel becomes unnecessary, its normal function in connection with steam being to provide for the drainage of condensation from the upper 30 chamber 31. Also when the chamber 31 is ported to the atmosphere, the valve bores 40 are plugged and thus when the valves 21 and 22 drop by gravity, assisted by the springs 39, upon failure of steam in the 35 high pressure steam space 13 by closing of the main throttle, the steam already within the cylinders is simply by-passed through the valves and the side channels 17 and 18 until it is exhausted, without the addition 40 of other steam as previously described, and vacuum and compression within the main cylinders is thus relieved.

In order to guard against possible failure of operation of the reducing valve, a pop 45 valve 60 is preferably utilized in connection with the chamber 31 as seen in Fig. 1.

I claim:—

1. A drifting device of the character described, comprising a valve block having 50 spaced valve bores and upper and lower chambers communicating with the upper and lower portions of said valve bores and having an intake opening, said block also having channels communicating with said 55 valve bores, double seating valves working in said bores for controlling communication between the said channels, and having pistons at one end adjacent the upper chamber, springs in the bores engaging the 60 valves at one end, said block having passages between its said chambers and the said channels also controlled by the valves and opening at one side of the said valve and piston, and said valves having lower hol-

low ends slidably interfitting the lower portions of the bores and provided with apertures in the walls thereof communicating with the lower chamber.

2. A drifting device of the character described, comprising a valve block having 65 spaced valve bores and a chamber communicating with the upper portions of said valve bores, and also having channels communicating with said valve bores, double seating valves working in said bores for 70 controlling communication between the said channels, and having pistons at one end adjacent the said chamber, springs in the bores engaging the valves at one end, said block having passages between its said 75 chamber and the said channels also controlled by the valves and opening at one side of the said valve pistons, means for supplying steam to the said chamber, each of said valves having an axial bore there- 80 through, and a pilot valve normally seated at one end of each of the valve bores.

3. A drifting device of the character described, comprising a valve block having a chamber, valve bores in communication 90 with the chamber adjacent their upper ends and connecting passages between the valve bores, said block also having channels at the sides of and communicating with said valve bores, double seating valves movable in said 95 bores and having axial openings there- through, pilot valves controlling the said axial openings of the main valve, said block having ports between its said chamber and one of the connecting passages, and means 100 for supplying low pressure steam to said chamber.

4. In a locomotive drifting device, a by-pass and relief valve having by-pass channels and a steam chamber, double seating 105 valves controlling communication between said channels and between the channels and said steam chamber, and having axial openings, pilot valves controlling the axial open- 110 ings of the main valve, said openings of the valve being in communication with the said steam chamber, and means for supplying low pressure steam to the said chamber.

5. A drifting device including a valve 115 block having a valve bore and valve seats spaced apart in the length of said bore and a chamber below the valve seats, said block having a steam passage leading between the valve seats, and a valve movable vertically in said bore, having valve members coöperating with said seats and having a lower skirt portion whose annular wall has upper apertures therethrough communicating with said chamber and whose lower portion slid- 120 ably interfits the lower portion of the valve 125 bore below the chamber.
